UNITED STATES PATENT OFFICE.

PAUL DE MARTINI, OF JAMAICA, NEW YORK.

DRIER FOR ALIMENTARY PASTE.

1,237,874.

Specification of Letters Patent. Patented Aug. 21, 1917.

Application filed November 13, 1916. Serial No. 130,978.

To all whom it may concern:

Be it known that I, PAUL DE MARTINI, a citizen of the United States, residing at Jamaica, in the county of Queens and State 5 of New York, have invented certain new and useful Improvements in Driers for Alimentary Pastes; and I do hereby declare the following to be a full, clear, and exact description of the invention, such as will enable 10 others skilled in the art to which it appertains to make and use the same, reference being had to the accompanying drawings, and to characters of reference marked thereon, which form a part of this specification. 15

The present invention has reference, generally, to drying apparatus for alimentary paste; and the invention relates, more particularly, to an improved construction of apparatus for drying and seasoning macaroni, spaghetti, noodles, and other paste products, expeditiously, with little handling, and with a minimum of loss or waste through breakage. 20

25 The invention has for its principal object to provide a simple and compact construction of drying apparatus for long, short or cut paste products, provided with a novel means for controlling and directing air currents against the material to be dried, in such a manner that, while the air may be passed in a direct and continuous draft against the material, whereby the quickest and most efficient drying effects are obtained, 30 it is so controlled and directed that the moving air has no tendency to agitate the macaroni, or the like, so as to cause breakage, of the same, and waste or loss consequent upon such breakage.

40 A further object of the invention is to provide in combination with the racks, upon which the material to be dried is arranged, of a regulatable means for controlling an air current passed through said racks and the 45 material supported thereby, said means being so constructed that it may be closed entirely to the passage of an air current therethrough when desired, and said means being also arranged or divided into sections or independent areas separately operable, so that the air current may be shut off from direct access to certain parts of the racks and yet permitted to pass through other parts of the 50 racks.

55 Other objects of this invention, not at this time more particularly enumerated, will be

clearly understood from the following detailed description of the same.

With the various objects of the said invention in view, the same consists, primarily, 60 in the novel construction and arrangement of drying apparatus for alimentary paste hereinafter set forth; and the invention consists, furthermore in the novel arrangements and combinations of the various devices and 65 parts, as well as in the details of the construction of the same, all of which will be hereinafter more fully described, and then finally embodied in the claims appended to this specification. 70

The invention is clearly illustrated in the accompanying drawings, in which:

Figure 1 is a front elevation of my novel drying apparatus; Fig. 2 is a rear end elevation of same; Fig. 3 is a vertical longitudinal section through the same; and Fig. 4 is a horizontal section through the same, looking downward. 75

Fig. 5 is a vertical longitudinal section of my novel drying apparatus, illustrating, 80 more particularly, a modified form of rack for supporting trays containing short and cut paste products for drying.

Fig. 6 is a vertical longitudinal section of my novel drying apparatus, illustrating the 85 racks movable upon rollers.

Similar characters of reference are employed in all of the hereinabove described views, to indicate corresponding parts. 90

Referring now to said drawings, the reference character 1 indicates the side inclosing walls, 2 the roof or ceiling and 3 the floor, all providing an inclosed main compartment 4, the ends of which are closed by my novel air controlling and directing 95 means to be subsequently described.

Arranged within said compartment 4, so as to extend transversely therethrough are the racks for supporting the macaroni, and the like. These racks comprise the vertical 100 members 5 and the horizontal members or rails 6 extending therebetween. The said racks thus constructed are preferably arranged in pairs, spaced apart to provide an intervening compartment or alley 7 between 105 the members of each pair of racks. The racks are also arranged so as to be of less length than the width of the compartment 4, thereby providing, at one end thereof, in any event, an aisle or passageway 8, giving 110 access thereto and to each compartment or alley 7. It will also be understood that said

BEST AVAILABLE COP

2

racks may, if desired, be made movable by providing a rack 33 with rollers or casters 34, as shown in Fig. 6 of the drawings so as to be capable of being wheeled into or out of the main compartment 4, which thus provides an arrangement whereby the racks may be loaded or unloaded outside of the main compartment, such an arrangement of racks being already well-known, and applied to various types of drying apparatus, hence, I do not claim to originate such a construction, and merely suggest that it may be readily employed in my present novel drying apparatus.

15 The reference character 9 indicates the rack rods which are straddled between the rails 6 of the racks, and upon which the macaroni 10 is suspended within the racks for drying.

20 The rear end of the compartment 4 is closed by a novel construction of regulatable air controlling and directing means. This consists of a suitable frame-work or supporting structure 11, which divides said end 25 of the compartment into a plurality of rectangular openings 12. Arranged within each opening 12 are a plurality of pivoted laterally extending louver-boards or slats 13, all connected together by a suitable link-rod 14 pivotally secured thereto, whereby 30 said louver-boards or slats 13 of each opening 12 may be adjusted by turning the same upon their pivots to open, close and regulate the same to the passage of air through 35 said openings 12. As shown in the drawings, the arrangement of said louver-boards or slats 13 in each opening 12 is preferably similar to the construction of the ordinary Persian blind, although it must also be understood that other ways of mounting said 40 regulatable louver-boards or slats 13 may be employed, such, for example, as a manner of mounting similar to that provided by the construction of Venetian blinds. Said 45 louver-boards or slats 13 may be made of any material desired, such as metal, wood, etc. The openings 12 may be made of any 50 desired area, and consequently may be increased or decreased in number within the entire area to be closed thereby, as may be desired, or as may seem most convenient and suitable to the location and size of the 55 novel drying apparatus.

The forward end of said compartment 4 is likewise closed by the novel regulatable air controlling and directing means, comprising a suitable frame-work or supporting structure 11, which divides the same into a plurality of openings 12, in each of which 60 are arranged said pivoted louver-boards or slats 13 connected together by link-rods 14. There is this difference to be noted, however, in the arrangement thus described, namely, that at this forward end of the compartment 4, said frame-work or supporting

structure 11 is so combined or arranged as to provide a main door-opening 15 in which is hinged a door-frame 16, the body of which is formed by said pivoted louver-boards or slats 13. This main door-opening 15 gives 70 access to the interior of said compartment, so that the material to be dried may be taken therethrough into or out of the compartment 4. In addition to this main door-opening 15 there is also provided, in said frame-work or supporting structure, a very 75 much smaller door or wicket opening 17 in which is hinged a small door-frame 18, the body of which is also formed by said pivoted louver-boards or slats 13. This small door 80 or wicket, thus provided, may be used by the operator of the apparatus to enter the compartment 4 to observe the effects of the drying processes upon the material, and being barely large enough to admit the passage of the person, the air currents and circulation is in no material degree disturbed by its use, as might be the case if the large main door were used while the drying processes were being carried on.

90 Preferably a lateral aisle or passageway 19 is provided between each end of the compartment 4, thus closed, and the adjacent rack, said aisles or passageways communicating with said longitudinal main aisle or 95 passageway 8.

99 Located in the compartments or alleys 7, on each side thereof, so as to face the adjacent sides of the macaroni supporting racks, and coextensive therewith are laterally extending frame-works or supporting structures 20, divided into a plurality of openings 21 in which are arranged pivoted laterally extending louver-boards or slats 22, those of each opening 21 being connected together by suitable link-rods 23 pivotally secured thereto. Such structures thus providing regulatable air controlling and directing means adjacent to each rack.

100 Located in each compartment or alley 7, 110 between the said air controlling and directing means above described, is an air circulating or driving-fan 24, rotatably mounted in bearings 25 secured to opposite portions of said frame-works or supporting structures 20, in such a manner that said fans rotate laterally between the members of each pair of racks. Said fans may be driven by any suitable means from a source 115 of power either within or without the compartment 4, although as illustrated the same are shown driven by a sprocket 26, over which runs the driving chain 27, extending exteriorly of said compartment 4 to some suitable driving means. The fans 24 are 120 preferably capable of rotation in either direction.

125 In operating my novel drying apparatus the louver-boards or slats 13, at the end of the compartment 4, are adjusted to provide 130

3

the desired amount of opening to the passage of air therethrough, and in like manner, the louver-boards or slats 22, adjacent to each rack, are adjusted to provide the desired amount of opening to the passage of air therethrough, and at the same time set in the proper inclination to produce the desired direction of air current. These adjustments having been made, the fans 24 10 are set in motion, with the result that a current of air is caused to flow through said compartment 4, by virtue of the propulsive effect of said fans, the same entering at one end thereof from the outside atmosphere, 15 then passing through the racks in contact with the macaroni or similar material supported thereby, and thence outward from the compartment 4 through the opposite end thereof. In this manner a direct continuously flowing and constantly renewed current of air is passed in contact with the macaroni or the like, said louver-boards 13 and 22 tending not only to break the force 20 of the draft or current of air thus set in motion, so that a not too violent contact 25 thereof with the macaroni or the like occurs, which would tend to shatter or break the same, with consequent waste and loss, but also tending to deflect the air from too 30 straight a path of movement, and thereby force the same with proper distributive effect into contact with the entire mass of macaroni or the like supported within the racks. It will thus be apparent that the 35 moving stream or current of air thus gently maintained in contact with the macaroni or the like will serve not only to absorb the moisture from the same, but will also carry off and out of said compartment the moisture laden air and consequently renew the 40 current or stream thereof with drier air. Of course a too rapid drying of the macaroni or the like is known to deleteriously affect the same, but such tendency to too 45 rapid drying may be quickly checked by regulating and adjusting the several sections of louver-boards or slats 13 and 22, to properly obstruct a too rapid flow of the air. In this respect my apparatus is capable 50 of great flexibility of adjustment, since the louver-boards or slats 13 and 22 are arranged in independently adjustable sections. For example, the entrance of the air at one end of the compartment 4 may be obstructed, while its exit at the other end of the 55 same is expedited, or vice versa, by means of opposite adjustment of the louver-boards or slats 13, or if one portion of the macaroni or the like, as supported in the racks, is drying more rapidly than another portion, then the louver-boards or slats 13 and 22, of the 60 openings opposite or nearest to the quickly drying portion may be closed to divert the air current, more directly to the slower drying portions through the remaining open- 65 louver-boards or slats, and so on, all according to the conditions presented by each batch of material to be dried. The fans 24 also being reversible in action, the direction of the air current may be reversed so 70 that all sides of the macaroni or the like may receive uniform treatment. I also provide within the compartment 4, and preferably within the inner compartment or alleys 7, steam radiators 28, or 75 other suitable heating units, which may be utilized to raise the temperature of the air to effect quicker drying. In drying macaroni or the like, the process usually divides itself into two or more 80 drying periods. During the first period the air currents tend to absorb and carry off the moisture nearest the surface of the macaroni, leaving a considerable amount of moisture within the internal parts or core 85 of the dough. If, after this surface drying has been accomplished to a proper degree, the air currents are continued the surface of the macaroni or the like becomes too dry, tends to crack and crumble away from the 90 still moist internal parts or core, and therefore quickly ruins the batch. Consequently the drying air currents must be stopped and the macaroni or the like inclosed in quiet air for a time sufficient to permit the moisture in the internal parts or core of the dough to come to the surface, after which the second drying period may be inaugurated by renewing the flow of the air currents, and this interruption of the air currents may be required several times according 95 to the conditions. Under these requirements of proper drying my apparatus readily lends itself to the proper inclosing of the macaroni or the like during the rest 100 periods without necessity of handling or removing the same from the supporting racks, since all that is necessary to be done is to close fully said louver-boards 13 and 22 and stop the fans 24, thereby safely and properly 105 confining the macaroni or the like in still air until the inner moisture comes to the surface thereof, and it is again proper to continue the drying process, by renewing the air currents in contact therewith. 110 While it is preferable to employ the fans 24 within the compartment 4, as above described, and as shown in the drawings; it must be understood that the scope of my invention, so far as it applies broadly to the 115 use of the louver-boards or slats 13 and 22 for controlling and regulating the air currents passed through the compartment 4 in contact with the material racked therein, is intended to include any method or means 120 for generating and circulating air currents through said compartment 4, whether said air currents be generated within the compartment, or without said compartment and thence directed therethrough. 125 130

Referring now to Fig. 5 of the drawings, I have illustrated therein my novel drying apparatus constructed substantially as above described, as is indicated by the similar reference characters applied thereto, but equipped with a slightly modified construction of rack members. In place of the rack members above described and which are adapted more particularly for the support of long macaroni, spaghetti and the like, I have here shown a rack construction for the support of small cut alimentary paste products such as noodles, short lengths, etc., the same comprising suitably disposed vertical standard members or supports 29, between which extend supporting rails 30. The said standards or supports 29 are arranged opposite each other, so as to dispose opposite each other in like manner, said supporting rails 30. The supporting rails 30 of the inner side of the racks, however, are positioned in a horizontal plane somewhat higher than the opposite supporting rails of the outer sides of the racks. Consequently each pair of oppositely positioned supporting rails 30 are adapted to support a tray 31, having an open mesh bottom 32, in a slightly downwardly and outwardly tilted or inclined position, which affords the best arrangement for supporting the paste in proper exposure to the air currents directed through the openings between the louver-boards or slats 13 and 22.

I am aware that some changes may be made in the arrangements and combinations of the various devices and parts, as well as in the details of the construction of the same, without departing from the scope of the present invention as set forth in the foregoing specification, and as defined in the claims appended hereto. Hence, I do not limit my invention to the exact arrangements and combinations of the several devices and parts as described in the foregoing specification, nor do I confine myself to the exact details of the construction of the said parts as illustrated in the accompanying drawings.

I claim:

1. In a device of the kind described, a main compartment, regulatable means at each end of said compartment through which air may pass, said means being substantially coextensive with the area of the ends of said compartment, racks within said compartment for supporting material in exposure to air passed therethrough, and regulatable means adjacent to and coextensive with a side of each rack by means of which the air current passed through said compartment is controlled and directed through each rack.
2. In a device of the kind described, a main compartment, regulatable means at each end of said compartment through which air may pass, said means being substantially coextensive with the area of the ends of said compartment, racks within said compartment for supporting material in exposure to air passed therethrough, a plurality of independently regulatable means adjacent to and in totality coextensive with a side of each rack by means of which the air current passed through said compartment is controlled and directed through each rack, and means for generating a current of air through said compartment.
3. In a device of the kind described, a main compartment, regulatable means at each end of said compartment through which air may pass, said means being substantially coextensive with the area of the ends of said compartment, racks within said compartment for supporting material in exposure to air passed therethrough, regulatable means adjacent to and coextensive with a side of each rack by means of which the air current passed through said compartment is controlled and directed through each rack, and rotary fans intermediate of said racks for forcing an air current through said compartment.
4. In a device of the kind described, a main compartment, a plurality of independently regulatable means at each end of said compartment through which air may pass, said means in totality being substantially coextensive with the area of the ends of said compartment, racks within said compartment for supporting material in exposure to air passed therethrough, and a plurality of independently regulatable means adjacent to and in totality coextensive with a side of each rack by means of which the air current passed through said compartment is controlled and directed through each rack.
5. In a device of the kind described, a main compartment, a plurality of independently regulatable means at each end of said compartment through which air may pass, said means in totality being substantially coextensive with the area of the ends of said compartment, racks within said compartment for supporting material in exposure to air passed therethrough, a plurality of independently regulatable means adjacent to and in totality coextensive with a side of each rack by means of which the air current passed through said compartment is controlled and directed through each rack, and means for generating a current of air through said compartment.
6. In a device of the kind described, a main compartment, a plurality of independently regulatable means at each end of said compartment through which air may pass, said means in totality being substantially coextensive with the area of the ends of said compartment, racks within said compartment for supporting material in exposure to air passed therethrough, a plurality of independently regulatable means adjacent to and in totality coextensive with a side of each rack by means of which the air current passed through said compartment is controlled and directed through each rack, and rotary fans intermediate of said racks for forcing an air current through said compartment.

stantially coextensive with the area of the ends of said compartment, racks within said compartment for supporting material in exposure to air passed therethrough, and regulatable means adjacent to and coextensive with a side of each rack by means of which the air current passed through said compartment is controlled and directed through each rack, and means for generating a current of air through said compartment.

3. In a device of the kind described, a main compartment, regulatable means at each end of said compartment through which air may pass, said means being substantially coextensive with the area of the ends of said compartment, racks within said compartment for supporting material in exposure to air passed therethrough, regulatable means adjacent to and coextensive with a side of each rack by means of which the air current passed through said compartment is controlled and directed through each rack, and rotary fans intermediate of said racks for forcing an air current through said compartment.

4. In a device of the kind described, a main compartment, a plurality of independently regulatable means at each end of said compartment through which air may pass, said means in totality being substantially coextensive with the area of the ends of said compartment, racks within said compartment for supporting material in exposure to air passed therethrough, and a plurality of independently regulatable means adjacent to and in totality coextensive with a side of each rack by means of which the air current passed through said compartment is controlled and directed through each rack.

5. In a device of the kind described, a main compartment, a plurality of independently regulatable means at each end of said compartment through which air may pass, said means in totality being substantially coextensive with the area of the ends of said compartment, racks within said compartment for supporting material in exposure to air passed therethrough, a plurality of independently regulatable means adjacent to and in totality coextensive with a side of each rack by means of which the air current passed through said compartment is controlled and directed through each rack, and means for generating a current of air through said compartment.

6. In a device of the kind described, a main compartment, a plurality of independently regulatable means at each end of said compartment through which air may pass, said means in totality being substantially coextensive with the area of the ends of said compartment, racks within said compartment for supporting material in exposure to air passed therethrough, a plurality of independently regulatable means adjacent to and in totality coextensive with a side of each rack by means of which the air current passed through said compartment is controlled and directed through each rack, and rotary fans intermediate of said racks for forcing an air current through said compartment.

adjacent to and in totality coextensive with a side of each rack by means of which the air current passed through said compartment is controlled and directed through 5 each rack, and rotary fans intermediate of said racks for forcing an air current through said compartment.

7. In a device of the kind described, a main compartment, a frame work at each 10 end of said compartment providing a plurality of openings, a plurality of pivoted adjustable laterally extending louver-boards mounted in each opening, a link-rod pivotally connecting together said louver-boards 15 of each opening, racks within said compartment for supporting material in exposure to air passed therethrough, a supporting structure adjacent to and coextensive with a side of each rack adapted to provide a 20 plurality of openings, a plurality of pivoted adjustable longitudinal slats mounted in said openings of said supporting structures, and a link-rod pivotally connecting together the slats of each of said openings, all for 25 the purposes described.

8. In a device of the kind described, a main compartment, a frame work at each end of said compartment providing a plurality of openings, a plurality of pivoted 30 adjustable laterally extending louver-boards mounted in each opening, a link-rod pivotally connecting together said louver-boards of each opening, racks within said compartment for supporting material in exposure to 35 air passed therethrough, a supporting structure adjacent to and coextensive with a side of each rack adapted to provide a plurality of openings, a plurality of pivoted adjustable longitudinal slats mounted in said 40 openings of said supporting structures, a link-rod pivotally connecting together the slats of each of said openings, and means for producing a moving current of air 45 through the spaces provided between said louver-boards and between said slats when the same are in open positions, for the purposes described.

9. In a device of the kind described, a main compartment, a frame work at each 50 end of said compartment providing a plurality of openings, a plurality of pivoted adjustable laterally extending louver-boards mounted in each opening, a link-rod pivotally connecting together said louver-boards 55 of each opening, racks within said compartment for supporting material in exposure to air passed therethrough, a supporting structure adjacent to and coextensive with a side of each rack adapted to provide a 60 plurality of openings, a plurality of pivoted adjustable longitudinal slats mounted in said openings of said supporting structures, a link-rod pivotally connecting together the slats of each of said openings, and rotary 65 fans between said supporting structures

adapted to propel a current of air through the spaces provided between said louver-boards and between said slats when the same are in open position, all for the purpose described.

10. In a device of the kind described, a main compartment, a frame work at each end of said compartment providing a plurality of openings, a plurality of pivoted adjustable laterally extending louver-boards 70 mounted in each opening, a link-rod pivotally connecting together said louver-boards of each opening, racks within said compartment for supporting material in exposure to air passed therethrough, a supporting structure adjacent to and coextensive with a side of each rack adapted to provide a plurality of openings, a plurality of pivoted adjustable longitudinal slats mounted in said 75 openings of said supporting structures, a link-rod pivotally connecting together the slats of each of said openings, rotary fans between said supporting structures adapted to 80 propel a current of air through the spaces provided between said louver-boards and between said slats when the same are in open 85 positions, and means within said compartment for raising the temperature of the air passing therethrough, all for the purposes described.

11. In a device of the kind described, a main compartment, regulatable means at each end of said compartment through which air may pass, a pair of laterally extending racks within said compartment, supporting 90 structures adjacent to and coextensive with the inner opposite sides of said racks, said supporting structures providing a plurality of openings, pivoted adjustable laterally extending slats mounted in each opening, link-rod pivotally interconnecting said slats of each opening to provide means for simultaneously and uniformly adjusting the slats of each opening independently of the slats of the other openings, and a rotary fan 95 mounted between said supporting structures and their slat closed openings adapted to rotate in a lateral vertical plane.

12. In a device of the kind described, a main compartment, regulatable means at 100 each end of said compartment through which air may pass, a pair of laterally extending racks within said compartment, supporting structures adjacent to and coextensive with the inner opposite sides of said racks, said 105 supporting structures providing a plurality of openings, pivoted adjustable laterally extending slats mounted in each opening, link-rod pivotally interconnecting said slats of each opening to provide means for simultaneously and uniformly adjusting the slats of each opening independently of the slats of the other openings, a rotary fan mounted 110 between said supporting structures and their slat closed openings adapted to rotate in a 115 lateral vertical plane.

13. In a device of the kind described, a main compartment, regulatable means at 120 each end of said compartment through which air may pass, a pair of laterally extending racks within said compartment, supporting structures adjacent to and coextensive with the inner opposite sides of said racks, said 125 supporting structures providing a plurality of openings, pivoted adjustable laterally extending slats mounted in each opening, link-rod pivotally interconnecting said slats of each opening to provide means for simultaneously and uniformly adjusting the slats of each opening independently of the slats of the other openings, a rotary fan mounted between said supporting structures and their slat closed openings adapted to rotate in a 130 lateral vertical plane.

6
lateral vertical plane, and aisles or passageways through said compartment giving access to said racks.

13. In a device of the kind described racks 5 for supporting the material spaced apart to provide an intermediate space, a rotatable fan disposed in a plane parallel to the sides of said racks and located in said intermediate space, and regulatable air controlling means between said fan and said racks.

14. In a device of the kind described racks 10 for supporting the material spaced apart to provide an intermediate space, a rotatable

fan disposed in a plane parallel to the sides of said racks and located in said intermediate space, and regulatable air controlling means between said fan and said racks, comprising a plurality of pivoted louver boards. 15

In testimony, that I claim the invention set forth above I have hereunto set my hand 20 this 8th day of November, 1916.

PAUL DE MARTINI.
